United States Patent Office

Des. 211,272
Patented June 4, 1968

211,272

COVERED CASSEROLE

Willis A. Stageberg, 3141 Rhode Island Ave. S.,
Minneapolis, Minn. 55426

Filed July 27, 1967, Ser. No. 8,025

Term of patent 14 years

(Cl. D44—1)

FIG. 1

FIG. 2

FIG. 3

←7 FIG. 4

FIG. 5

FIG. 6

FIG. 7

I claim:

The ornamental design for a covered casserole, as shown.
